COMBINATION WALLBOARD AND INSULATING MATERIAL

Edward M. Zier, New Albany, Ind., assignor of one-half to Kozine B. Zier and Edward M. Zier, Jr., both of New Albany, Ind.

Application December 17, 1936, Serial No. 116,420

5 Claims. (Cl. 20—4)

This invention relates to a combination wall board and insulating material.

An object of the invention is to provide a combination wall board and insulating bat of a durable, efficient, inexpensive nature adapted to be easily applied as a unit with the insulating bat disposed between and with its sides in tight fitting engagement with adjacent studding or other structural elements.

Another object of the invention is to provide in a combination wall board and insulating bat of the character referred to, means of a simple efficient character for strengthening the wall board and for supporting the bat.

A further object of the invention is to provide an insulating bat with improved means for reinforcing and supporting the same.

The invention, with other objects and advantages thereof, and the particular construction, combination and arrangement of parts comprising the same, will be understood from the herein-after contained detailed description, when considered in connection with the accompanying drawing forming part hereof and illustrating embodiments of the invention.

In the drawing:

Figure 1 is a front elevation of a piece of combination wall board and insulating material constructed in accordance with the present invention.

Fig. 2 is a transverse sectional view on the line 2—2 of Fig. 1.

Fig. 3 is a fragmentary transverse sectional view showing the combination wall board and insulating material in the course of applying the same to joists or studding, the insulation being shown entered between adjacent studding with one side compressed against one of the studding strips and flexed rearwardly.

Fig. 4 is a similar view showing the wall board and insulation unit secured in position, a plurality of the units being shown.

Fig. 5 is a fragmentary transverse sectional view of two pieces of the combination wall board and insulating bat disposed lengthwise with the adjacent side edge portions of the sheets of wall board abutting, and with the adjacent sides of the insulating bats pressed together and flexed rearwardly.

Fig. 6 is a transverse section illustrating a slightly modified construction.

Fig. 7 is a fragmentary longitudinal section of the construction illustrated in Fig. 6.

Fig. 8 is a transverse section of another modification in which the wall board is provided with

longitudinally extending reinforcing ribs on its rear face.

Fig. 9 is a fragmentary longitudinal section of the construction illustrated in Fig. 8.

While specific embodiments of the invention are illustrated in the drawing, it will of course be understood that changes and modifications may be made in the particular constructions shown, and the invention may be embodied in other forms as will appeal to those skilled in the art and falling within the scope of the appended claims, without departing from the spirit of the invention.

The invention contemplates a construction comprising plaster wall board or any of the conventional types of wall board that are of a hard, stiff, self-supporting nature, and an insulating bat secured to the inner face of the wall board element. The insulating bat is formed of felted semi-hardened rock wool or other suitable yieldable insulating material.

Referring to a detail description of the particular embodiment of the invention illustrated in Figures 1 to 5 of the drawing, 1 designates the wall board and 2 is the bat of insulating material on the inner face thereof. The insulating bat 2 is wider than the wall board 1 and is secured thereto inwardly of opposite side marginal portions thereof so that marginal portions 3 of the bat at opposite sides thereof inwardly of the side edges of the wall board are left free thereof, said marginal portions projecting laterally beyond opposite side edges of the wall board. The free marginal side portions 3 of the bat are spaced from the inner face of the wall board, as shown, the bat being formed with the side portions 3 reduced in thickness to provide for this.

The composite wall board and insulating bat is adapted to be applied as a unit to a wall as illustrated in Fig. 3 of the drawing, with the wall board secured to the inner face of studding 4 and the insulating bat disposed between adjacent studding, the special construction providing for the ready introduction of the insulating bat between adjacent studding with the sides of the bat in tight fitting engagement with the sides thereof. In applying the unit, as illustrated in Fig. 3, one side of the insulating bat is entered between the studding and forced laterally and compressed and flexed against one of the studding strips sufficiently to permit the other side of the bat to enter between the studding. The wall board is then shifted laterally in the opposite direction to adjust it to proper position relatively to the inner faces of the adjacent studding and secured thereto by nails 5 or equivalent fastening means, the in-

5 insulating bat being positioned as illustrated in Fig. 4 with each side flexed rearwardly and tightly compressed against one of the studding strips. As will be understood, the spacing of the free 10 marginal side portions 3 of the bat from the inner face of the wall board facilitates the flexing and compression of the sides of the bat in introducing the same between the studding, and the compressed sides of the bat are disposed rearwardly of the inner nailing faces of the studding so as not to interfere with the fitting of the wall board closely against the same. In the particular construction shown, the free side marginal portions 15 3 of the insulating bat extend inwardly from the side edges of the wall board for a distance of about twice the width of the nailing faces of the studding 4.

20 In Fig. 5 of the drawing is illustrated how the wall board and insulating units may be secured to a wall arranged directly side by side with the free side marginal portions 3 of the insulating bats of adjacent units pressed tightly together and flexed rearwardly away from abutting edges of the sheets of wall board.

25 In the modified construction illustrated in Figs. 6 and 7, the wall board designated 6 is formed of hardened rock wool and the insulating bat 7 of semi-hardened rock wool. In this construction, the wall board is provided on its inner face with transverse ribs 8 formed integral therewith and imbedded in the insulating bat, said ribs serving to reinforce the wall board and also as means for supporting and strengthening the insulating bat.

30 The modified construction shown in Figs. 8 and 9 of the drawing, is similar to the construction illustrated in Figs. 6 and 7, except that in this instance, the wall board is provided with longitudinal strengthening and supporting ribs. 40 In these views, 9 designates the wall board, 10 the ribs on the wall board, and 11 the insulating bat.

45 It will be noted that the particular construction and arrangement of parts hereinbefore set forth, affords a combined wall board and insulation that can be easily applied as a unit and at the same time provides for a tight fit between the sides of the insulating bat and adjacent studding or other structural parts. The construction is of a durable, practical nature and can be produced at low cost.

50 What I claim is:

1. A composite structural material including wall board and a bat of yieldable insulating material on the inner face thereof, the bat of insulating material being secured to the wall board inwardly of opposite side marginal portions of the wall board leaving side marginal portions of the bat facing said marginal portions of the wall board free relatively thereto, and said free opposite side marginal portions of the insulating bat being spaced inwardly from the face of the wall board and adapted to be compressed.

2. A composite structural material including wall board and a bat of yieldable insulating ma-

5 terial on the inner face thereof, the bat of insulating material being secured to the wall board inwardly of opposite side marginal portions of the wall board leaving opposite side marginal portions of the bat free relatively to said side marginal portions of the wall board, said free side marginal portions of the bat being spaced from the face of the wall board and projecting laterally beyond the side edges thereof.

3. The combination with studding of a composite structural material including wall board and a bat of yieldable insulating material on the inner face thereof, the bat of insulating material being secured to the wall board inwardly of opposite side marginal portions of the wall board 10 leaving opposite side marginal portions of the bat facing said marginal portions of the wall board free for movement relatively thereto, and said bat being of greater width than the distance between the studding, the wall board and insulating bat being applied as a unit with the wall board secured against the inner face of the studding, and the insulating bat disposed between and with side marginal portions thereof compressed against the side faces of adjacent studding.

4. The combination with studding of a composite structural material including wall board and a bat of yieldable insulating material on the inner face thereof, the bat of insulating material 30 being secured to the wall board inwardly of opposite side marginal portions of the wall board leaving opposite side marginal portions of the bat facing said marginal portions of the wall board free for movement relatively thereto, said 35 free side marginal portions of the bat projecting laterally beyond the side edges of the wall board, and said bat being of greater width than the distance between the studding, the wall board and the insulating bat being applied as a unit with the wall board secured against the inner face of the studding, and the insulating bat disposed between and with side marginal portions thereof compressed against the side faces of adjacent 40 studding.

45 5. A composite structural material including relatively rigid wall board and a bat of yieldable fibrous insulating material secured to the inner face thereof, the bat of insulating material being secured to the wall board inwardly of opposite side marginal portions of the wall board 50 leaving opposite side marginal portions of the bat facing said opposite side marginal portions of the wall board free from movement relatively thereto, said free side marginal portions of the bat being spaced inwardly from the face of the wall board and projecting laterally beyond the side edges thereof, the wall board having ribs projecting from its inner face located inwardly of the free side marginal portions of the bat of insulating material and imbedded in the bat of insulating material.

EDWARD M. ZIER.

CERTIFICATE OF CORRECTION.

atent No. 2,128,549.

August 30, 1938.

EDWARD M. ZIER.

It is hereby certified that the above numbered patent was erroneously issued to the inventor, said "Zier", as assignor of one-half interest to Kozine B. Zier and Edward M. Zier, Jr., whereas said patent should have been issued to Rozine B. Zier and Edward M. Zier, Jr., both of New Albany, Indiana, as assignees of one-half interest each in said invention, as shown by the record of assignments in this office; page 2, second column, line 4, claim 5, for the word "from" read for; and that the said Letters Patent should be read with this correction therein that the same may conform to the record of the case in the Patent Office.

Signed and sealed this 11th day of October, A. D. 1938.

Henry Van Arsdale

Seal

Acting Commissioner of Patents.
